UNITED STATES PATENT OFFICE.

GEORGE H. DROEGE, OF NEW YORK, N. Y.

DESIGN FOR A STOVE TOP-PLATE.

No. 40,225.

Specification for Design.

Patented Aug. 10, 1909.

Application filed April 12, 1909. Serial No. 489,537. Term of patent 7 years.

To all whom it may concern:

Be it known that I, GEORGE H. DROEGE, a citizen of the United States, residing at New York, in the county of New York and State of New York, have invented a new, original, and ornamental Design for Stove Top-Plates; and I do hereby declare the following to be a full, clear, and exact description of the same, reference being had to the accompanying drawing, forming a part thereof.

The design consists in providing the top plate of a stove, as a gas stove shown at 10, with holes for burners. The holes are formed with reverse curves upon each side shown at 11 with flanges 12 formed with their inner edges parallel with the holes 11 producing thereby a sunken rabbet following the curvature of the sides of the holes entirely about the holes. At the several corners of the holes curved ears 13 are provided on a plane with the flanges 12.

In the openings 11 and resting upon the flange 12 and ears 13 is a grate having its sides 14 produced with reverse curves to cor-

respond to the curves 12 of the sides of the hole, and with a central ring 15 equally spaced from the four sides. The whole grate is integral, the ring 15 being connected with the sides by means of bars 16 each formed with reverse curves and having the effect of extending inwardly beyond the ring 15 and terminating in extremities 17 curved adjacent the ring 15 and terminating in radially extending portions.

It is to be understood, of course, that each of the holes 11 is provided with one of the grates, and where not shown are omitted for the purpose of showing the curvature and ornamental effect of the border of the holes themselves into which the ornamental grate is seated.

I claim—

The ornamental design for a stove top-plate as shown and described.

GEORGE H. DROEGE.
